UNITED STATES PATENT OFFICE

JOHN S. PHELPS, OF WHITTIER, CALIFORNIA

BOX STAMPING MACHINE

Application filed July 9, 1928. Serial No. 291,219.

My invention relates to stamping devices, and it is a primary object of my invention to provide a stamping machine for automatically printing on a box, or other container, certain nomenclature relative either to the contents thereof, such as the classification or name of the articles enclosed, or relative to the box itself, such as the serial number, capacity, etc.

My invention finds a particular utility in the citrus fruit packing industry, and it is in this capacity that it will be particularly described without limiting myself thereto. In this industry one brand name, and label therefor, is used for a number of different varieties of fruit, and it is desirable to impress either on the box or label the name of the particular variety of fruit packed in the box. Thus, navel and valencia oranges are handled by the same packing house and are often packed under the same name of brand.

I have invented a machine for stamping a desired nomenclature or symbol on a box, this machine being attachable to any one of a number of types of already existing machines or devices used in citrus packing houses.

Thus, my invention may be applied to a strapping machine for strapping lids to boxes, or may be attached to a machine for applying the lids themselves, as well as other machines and devices at present in use. My stamping device may also be hand operated.

It is an object of my invention to provide a stamping machine for boxes or other members, this machine being attachable to existing machines or devices and operated by the movement of an actuating member on the existing machine or device itself.

Another object of my invention is to provide a stamping mechanism for boxes and other members which is normally disposed outside the path of travel of said boxes or members, but being movable into said path of travel to engage the same, and actuating means for moving said stamping means into and from said path of travel of said boxes or members.

A further object of my invention is to

provide a novel re-inking device operable by the movement of the box or other member being stamped.

Further objects and advantages of my invention will be made evident hereinafter.

Referring to the drawings, in which I have illustrated my stamping machine as applied to a strapping machine,—

Fig. 1 is a side elevational view of the strapping machine incorporating my invention.

Fig. 2 is a detailed view taken in the direction of the arrow 2 of Fig. 1.

Fig. 3 is a top view of the strapping machine incorporating my invention.

Fig. 4 is a sectional view taken on the line 4-4 of Fig. 1.

Fig. 5 is a perspective view of the re-inking device of my invention, and also illustrates the stamping means of my invention.

Referring particularly to Fig. 1 I have illustrated my invention as applied to a strapping machine 10, this machine having a frame 11 in which a series of horizontal rollers 12 are pivotally mounted. These rollers, together with side rollers 13, define a path of travel for a box 14 which has been packed with oranges or other fruit or articles 15, and held in place by a lid 16 applied to the box by a lidding machine, not shown. The box 14 moves along the frame 11 until it contacts a stop member 17, best shown in Figs. 1 and 5, at which time the box is medially positioned under the mechanism of the strapping machine, this mechanism being indicated generally by the numeral 18.

This mechanism is not a part of my invention and thus will not be described in detail. Essentially, it comprises a pair of stationary guides 19 which form a way along which a sliding element 20 reciprocates through the action of a prime mover, not shown. As the sliding element moves downward a suitable strap is placed across the top of the box 14 and secured to the side walls thereof. During this strapping operation a head 22, secured to the lower end of the sliding element moves from a position shown in full lines in Fig. 1 into a position shown by dot-

ted lines 23. This movement is utilized as a source of power for the operation of my stamping machine, indicated generally by the numeral 25.

This stamping machine has a leg 26 secured to the frame 11 and extending downward to the floor. Pivoted in a bearing 27 mounted on this leg is a bell crank 28, the shorter arm 29 of which has a bolt 30 passing therethrough. This bolt serves to pivot 10 a follower 31 which engages the underside of a member 32 secured to the head 22, this member and head cooperating to form an actuating member 33 for my invention.

A cam leg 35 extends downward from the frame 11 and has a cam surface 36 against which the follower 31 bears, being held in contact therewith by a spring 37 adjacent the bolt 30. As best illustrated in Figs. 2 and 4, this cam surface 36 is not vertical but extends toward the front of the machine, thus pivoting the follower 31 relative to the arm 29 as this follower is moved downward, due to contact with the actuating member 33. This pivoting action slides the follower toward a corner 38 of the member 32, and when the arm 29 is moved into the dotted line position indicated by the numeral 40, the follower is moved clear of the corner 38, at which time a tension spring 30 41 draws the arm 29 into its full line position.

The long arm of the bell crank 28 is indicated by the numeral 42 and extends upward between compression springs 43 and 35 44 which surround a shaft 45, this shaft passing through the upper end of the arm 42. The springs 43 and 44 are respectively compressed against a nut 46 and a pin 47.

Pivoted on a vertical shaft 50 mounted 40 in sockets 51 on the upper end of the leg 26 is an arm 52 having an operating arm 53 extending therefrom. This operating arm and the end of the shaft 45 are connected 45 together by a universal joint in the form of a ball-and-socket joint 54 so that as the arm 29 is moved into its dotted line position 40, thus moving the arm 42 into a dotted line position 55, the arm 52 is pivoted on the shaft 50 and swings into the path of travel 50 of the box 14.

A stamping means is mounted on the free end of the arm 52, this stamping means comprising a stamp 57 having raised letters 58 thereon. The shaft 50 is positioned adjacent the forward end of the box 14 so that the stamp 57 is brought into surface contact with the end of the box when the bell crank 28 is moved into its dotted line position indicated by the numerals 40 and 55, thus printing the desired nomenclature or symbol on the end of the box. As the follower 31 slips past the corner 38, and the bell crank 28 moves into its full line position, the arm 52 is pivoted about the shaft

50 and swings into its retracted position illustrated in Fig. 5. The springs 43 and 44 act as a resilient means between the bell crank 28 and the stamping means.

It should be understood that when the follower 31 moves past the corner 38, the head 22 of the actuating member 33 may continue to move downward into its dotted line position 23, during the time that the spring 41 moves the stamping means into its retracted position. When this actuating member is in its lowermost position, a chain 60 is drawn taut and releases the stop 17 so that when the actuating member 33 moves into its full line position the box 14 may be either manually or automatically pushed along its normal path of travel and onto a pair of rollers 61 pivotally mounted in the frame 11, after which it moves onto a conveyor plate 62 which moves the box away 85 from the strapping machine 10.

It will be readily apparent that the stamping means is normally disposed outside of the path of travel of the boxes and the actuating mechanism for conveying the 90 boxes moves the stamping means into and from said path of travel of the boxes.

I utilize this movement of the box for re-inking the stamp 57. This re-inking device is best illustrated in Fig. 5 and comprises a bracket 65 secured to the leg 26, this bracket having a horizontal bar 66 mounted on the upper end thereof. The bar 66 serves the dual purpose of limiting the retracted position of the arm 52, and supporting a pair of arms 68, in the outer ends of which is held a shaft 69. Pivoted on this shaft is a re-inking means in the form of a re-inking pad 70 having an actuating arm 71 extending therefrom.

A spring 72 connects a projection 73 on one of the arms 68 and the actuating arm 71 in such a manner that a toggle action takes place tending to move the re-inking pad 70 either tightly against the stamp 57, 110 or retracted therefrom in such a position as to allow the arm 52 to swing thereby.

The retracted position of this re-inking pad 70 is determined by an arm 75 of a stop member 76 mounted on a lever 77. This lever is bent to extend into the path of travel of the box 14 and is pivoted on a shaft 78, being normally held in the path of travel of the box by a tension spring 79. The lever 77 has a cam surface 80 thereon 120 against which the box 14 bears as it passes from the strapping machine 10. This pivots the lever 77 about the pin 78 in the direction indicated by the arrow 81 of Fig. 5, thus causing the arm 75 to move a pin 82 of the actuating arm 71 in an arcuate path, pivoting the re-inking pad 70 on the axis of the shaft 69. When the center line of the spring 72 has just passed the axis of this shaft, this spring will operate to move 125

130

the re-inking pad 70 into firm contact with the stamp 57, thus applying more ink to this stamp. As the box 14 is moving away from the lever 77, and just before a separation of the cam surface 80 and the side of the box takes place, the spring 79 moves the lever 77 again into the path of travel of the next box. This causes an arm 83, forming a portion of the member 76, to engage the pin 82 and move the actuating arm 71 a short distance until the toggle action of the spring 72 throws the re-inking pad 70 into its position as shown in Fig. 5, this position being determined by the arm 75.

It should be understood that my invention is not limited to the particular embodiment shown nor to attachment with the particular strapping machine shown. Any machine which defines a normal path of travel for a box or other member and which has a moving actuating member may be used for mounting my stamping machine 25.

Neither am I limited to the automatic operation illustrated. My stamping machine may be manually operated by having an operator move the bell crank 28. This may conveniently be done by stepping on the follower 31, but any means for moving the stamping means into and out of the path of travel of the box falls within the scope of this invention.

I claim as my invention:

1. In a box stamping machine, the combination of: a frame providing a path of travel for said box; a stamping means disposed outside of the path of travel of said box and being movable into said path of travel to engage a face of said box disposed normal to the path of travel of said box; actuating means for moving said stamping means into and from said path of travel; and re-inking means for said stamping means having an inking member and a part engaged by said box whereby to cause movement of said inking member into inking engagement with said stamping means.

2. In a box stamping machine, the combination of: a frame providing a path of travel for said box; an actuating member adapted to be moved when said box is thereadjacent; a stamping means normally disposed outside of the path of travel of said box and being actuated by the movement of said actuating member to move into the path of travel of said box and into engagement with the face of said box normal to the direction of movement of said box along said path of travel; an inking member for applying ink to said stamping means; a movable member adapted to be engaged by said box as it moves along said path of travel; and a connection between the inking member and said movable member for producing engagement of said inking member with said

stamping means in response to movement of said movable member.

3. In a box stamping machine, the combination of: a frame providing a path of travel for said box; an actuating member 70 adapted to be moved when said box is thereadjacent; a stamping means normally disposed outside of the path of travel of said box and being moved by said actuating member into the path of travel of said box 75 and into engagement with the face of said box normal to the direction of movement of said box along said path of travel; and means operable to allow a return of said stamping means prior to said actuating 80 member reaching the end of its movement.

4. In a box stamping machine, the combination of: a frame providing a path of travel for said box and providing a position of rest into which said box is moved; an 85 actuating member adapted to be moved when said box is thereadjacent; a stamping means normally disposed outside of the path of travel of said box and being actuated by the movement of said actuating member to 90 move into the path of travel of said box and into engagement with the face of said box normal to the direction of movement of said box along said path of travel; and means for withdrawing said stamping means 95 from engagement with said box before said box is moved from said position of rest.

5. In a box stamping machine, the combination of: a frame providing a path of travel for said box; an actuating member 100 adapted to be moved when said box is thereadjacent; a stamping means actuated by the movement of said actuating member to move into engagement with said box, said stamping means being withdrawn from engagement with said box before said box is moved; and re-inking means operated by the movement of said box to re-ink said stamping means.

6. In a stamping machine, the combination of: a frame adapted to support a member to be stamped; stamping means movable into and from engagement with said member; and re-inking means operable by the movement of said member relative to 115 said frame.

7. In a stamping machine, the combination of: a frame adapted to support a member to be stamped; stamping means movable into and from engagement with said member; and re-inking means pivoted adjacent said stamping means when in disengaged position, said re-inking means being operable by the movement of said member relative to said frame.

8. In a stamping machine, the combination of: a frame adapted to support a member to be stamped; stamping means movable into and from engagement with said member; and re-inking means pivoted ad- 130

jacent said stamping means when in disengaged position; a toggle device holding said re-inking means in either engaged or disengaged position relative to said stamping means; and a stop member controlling the disengaged position of said re-inking means.

9. A combination as defined in claim 8 in which said stop member controls the toggle action of said re-inking means, and in which 10 said stop member is moved by a movement of said member relative to said frame.

10. In a box stamping machine, the combination of: a frame providing a path of travel for said box; a stamping means disposed outside of the path of travel for said box and movable into said path to engage said box; an actuating means for moving said stamping means into and from said path; and re-inking means for said stamping means operated by the movement of said box.

11. In a box stamping machine, the combination of: a frame providing a path of travel for said box; a stamping means movable into said path of travel to engage said box; means for moving said stamping means into and from said path of travel; and re-inking means operated by the movement of said box to re-ink said stamping means.

12. A machine of the character described, including: a frame providing a path of travel for a box; a support attached to said frame; a stamp member pivoted to said support so as to swing from a position outside of the path of travel of said box into said path of travel so as to engage a face of said box disposed normal to said path of movement; mechanism on said frame having a working member moving through a working stroke; an actuating member for swinging said stamp member through an operating cycle; and connecting means forming part of said actuating member adapted to engage said working member of said mechanism whereby to impart movement to said actuating member.

13. A machine of the character described, including: a frame providing a path of travel for a box; a support attached to said frame; a stamp member pivoted to said support so as to swing from a position outside of the path of travel of said box into said path of travel so as to engage a face of said box disposed normal to said path of movement; mechanism on said frame having a working member moving through a working stroke; an actuating member for swinging said stamp member through an operating cycle; connecting means forming part of said actuating member adapted to engage said working member of said mechanism whereby to impart movement to said actuating member; release means for releasing said connecting means from engagement with said working part at a predetermined

position in the movement of said actuating member; and resilient means for returning said actuating member to original position.

14. A machine of the character described, including: a frame providing a path of travel for a box; a support attached to said frame; a stamp member pivoted to said support so as to swing from a position outside of the path of travel of said box into said path of travel so as to engage a face of said box disposed normal to said path of movement; mechanism on said frame having a working member moving through a working stroke; an actuating member resiliently connected to said stamp member for swinging said stamp member through an operating cycle; connecting means forming part of said actuating member adapted to engage said working member of said mechanism whereby to impart movement to said actuating member; release means for releasing said connecting means from engagement with said working part at a predetermined position in the movement of said actuating member; and resilient means for returning said actuating member to original position.

15. A machine of the character described, including: a frame providing a path of travel for a box; a support attached to said frame; a stamp member pivoted to said support so as to swing from a position outside of the path of travel of said box into said path of travel so as to engage a face of said box disposed normal to said path of movement; mechanism on said frame having a working member moving through a working stroke; an actuating member pivoted at an intermediate point, said actuating member having an arm connected to said stamp member so as to swing said stamp member, and having a second arm engaging said working member so as to receive movement from said working member; a spring for returning said actuating member to original position; and cam means for forcing said second arm from engagement with said working member.

16. A machine of the character described, including: a frame providing a path of travel for a box; a support attached to said frame; a stamp member pivoted to said support so as to swing from a position outside of the path of travel of said box into said path of travel so as to engage a face of said box disposed normal to said path of movement; mechanism on said frame having a working member moving through a working stroke; an actuating member pivoted at an intermediate point, said actuating member comprising a bell crank having an arm connected to said stamp member so as to swing said stamp member, and having a second arm engaging said working member so as to receive movement from said working member, said second arm being adapted

to be flexed in lateral direction; a spring for returning said actuating member to original position; and cam means for forcing said second arm from engagement with said working member.

17. In a box stamping machine, the combination of: a frame providing a path of travel for said box; a stamping means disposed outside of the path of travel of said box and being movable into said path of travel to engage said box; actuating means for moving said stamping means into and from said path of travel; and automatic re-inking means for said stamping means operating independently of said actuating means.

18. In a stamping machine, the combination of: a frame providing a path of travel for an article to be stamped; a stamp; means for actuating said stamp so as to accomplish stamping engagement thereof with said article; and automatic reinking means for said stamp, said reinking means being separate from and operating independently of said actuating means.

19. In a stamping machine of the character described, the combination of: a structure adapted to support a member to be stamped; a stamping member; means for moving said stamping member into engagement with said member to be stamped; a re-inking member for applying ink to said stamping member; a part adapted to be engaged and moved by said member to be stamped; and means operatively connecting said part and said re-inking member for causing said re-inking member to engage said stamping member.

20. In a stamping machine of the character described, the combination of: a structure adapted to support an article to be stamped, said structure providing a path of movement along which said article is moved into stamping position; a stamping member; operating means for moving said stamping member from a retracted position to a position of engagement with said article; a re-inking member adapted to engage said stamping member; a cam movably supported on said structure and having a sloping face adapted to be engaged by said article as it is moved relative to said stamping position; and means operatively connecting said cam member and said re-inking member whereby to produce engagement of said stamping member by said re-inking member in response to movement of said cam member by said article.

21. In a stamping machine of the character described, the combination of: a structure adapted to support an article to be stamped, said structure providing a path of movement along which said article is moved into stamping position; a stamping member; operating means for moving said

stamping member from a retracted position to a position of engagement with said article; a re-inking member adapted to engage said stamping member; a cam member pivoted on said structure to one side of said stamping member and having a sloping face adapted to be engaged by said article as it is moved relative to said stamping position; and means operatively connecting said cam member and said re-inking member whereby to produce engagement of said stamping member by said re-inking member in response to movement of said cam member by said article.

In testimony whereof, I have hereunto set my hand at Los Angeles, California, this 2nd day of July, 1928.

JOHN S. PHELPS.
